UNITED STATES PATENT OFFICE.

OSGOOD MORRILL, OF SALISBURY, MASSACHUSETTS.

CARRIAGE-BODY.

SPECIFICATION forming part of Letters Patent No. 324,333, dated August 11, 1885.

Application filed April 9, 1885. (No model.)

To all whom it may concern:

Be it known that I, OSGOOD MORRILL, of 5
Salisbury, in the county of Essex and State of
Massachusetts, have invented a new and use-
ful Improvement in Carriage-Bodies, which
will, in connection with the accompanying
drawings, be hereinafter fully described, and
specifically defined in the appended claim.

This invention has for its object an improve- 10
ment in carriage-bodies, which invention con-
sists in a section fitted in the cut-down opening
in the side panel, which facilitates ingress
to and egress from the body, said section being
so hinged to the body as to admit of its being
moved, on its hinge-pivot, in a vertical plane
15 when it is desired to open the cut-down space
for the purposes named, such vertical move-
ment of the hinged section being practical
when a horizontal movement thereof would be
20 impossible by reason of the obstacle which the
side bars present.

In the accompanying drawings, Figure 1 is
25 a side elevation of a "jump-seat" body with
my invention thereto applied, both seats being
shown as in position for use. Fig. 2 is a view
like the first, except that but one seat is in
position for use, and a portion of the top is
30 omitted. Fig. 3 shows my invention as ap-
plied to a one-seated open-buggy body. Fig.
30 4 is an enlarged detached view showing a por-
tion of the body and hinged section as united,
and with the hinged section as turned up.

In these views, *a a* represent the side
35 panels of the body. *b* represents the rear or
jumping seat, and *c* the front or turn-down
seat. *d d* represent the front standards of
the turn-down top, and *e e* represent the sec-
tions which are fitted into the cut-down open-
40 ings in panels *a*, and which are secured by
hinges *f* to said panels, the pivot *g* of the
hinges being arranged at the top line of the
panel, as shown.

The body may be of any desired form, pat-
tern, or style, and with or without a top, and
45 either a turn-down or canopy top may be em-
ployed, and the seats may be of any kind or
pattern, and either permanently in position,
as shown in Fig. 3, or of the well-known
jump and turn-down kind, as shown in Figs.
50 1 and 2.

It being necessary when my invention is
employed upon a carriage having either a

canopy top or turn-down top that the front
standards or front bow of the top be so ar-
ranged as to be either inside or outside the 55
path of the section *e* when the same is turned
up, and the front seat, if fixed in position,
must be of such width as not to extend within
the path of the hinged sections.

In Fig. 1 the hinged section *e* is shown by 60
dotted lines as turned forward, and in Fig. 3
it is shown by solid lines as turned up, and
resting against the dasher by the engagement
therewith of a stop on the section.

When used with single-seat bodies having 65
high panels, this section facilitates ingress and
egress as effectually as would a full-height
door in a top carriage, and when used with a
jump-seat carriage having high side panels it
70 obviates the necessity of turning forward the
front seat when the occupants of the rear seat
enter or leave the carriage, and when the rear
seat is jumped forward to serve as the sole
75 seat of the vehicle, this section closes the
cut-down space and renders the panel com-
plete in appearance.

I am aware of United States Patent No.
125,817, dated April 16, 1872, and I disclaim
the invention therein described and claimed,
my invention consisting in a removable sec- 80
tion of the side panel that is less in depth
than is the panel, and which is hinged at its
front end and top edge, thus rendering it feas-
ible to employ my invention in connection
with carriage-bodies the sides of which are 85
formed with a transverse or vertical curve,
while in said reference the entire panel is sub-
divided and the section is pivoted at its front
lower corner, which could only be available in
bodies the sides of which are a true vertical 90
plane.

I claim as my invention—

The combination, with a carriage-body hav-
ing cut-down side panels, of sections fitting in
and corresponding to said cut-down spaces
and pivoted at their front upper corner and
arranged to be opened and closed independ-
ently each of the other, substantially as speci- 95
fied.

OSGOOD MORRILL.
